[57] CLAIM

The ornamental design for a combined electrical outlet cover and mounting plate for strobe light for fire alarm systems or the like, as shown and described.

DESCRIPTION

FIG. 1 is a front elevational view of a combined electrical outlet cover and mounting plate for strobe light for fire alarm systems or the like showing our new design; FIG. 2 is a cross-sectional view thereof as taken along line 2—2 of FIG. 1;

FIG. 3 is a top plan view thereof, the bottom being a mirror image;

FIG. 4 is a side elevational view thereof, the opposite side being a mirror image;

FIG. 5 is a rear elevational view thereof.

FIG. 1

FIG. 2

FIG. 3

FIG. 4
